UNITED STATES PATENT OFFICE.

ALEXANDER H. DREUX, OF NEWARK, NEW JERSEY, ASSIGNOR TO SCOOP FOLDING BOX COMPANY, OF NEW YORK, N. Y.

ANTISIFTING BOX OR CARTON.

1,073,103.

Specification of Letters Patent. Patented Sept. 16, 1913.

Application filed January 18, 1910. Serial No. 538,679.

To all whom it may concern:

Be it known that I, ALEXANDER HERMAN DREUX, a citizen of the United States, and resident of Newark, in the county of Essex and State of New Jersey, have invented certain new and useful Improvements in Anti-sifting Boxes or Cartons, of which the following is a specification.

This invention relates to boxes or cartons for containing and delivering groceries and the like, and my improvement consists in certain novel means preventing sifting of the contents while the closed packages are in transit or being handled.

In the drawing accompanying this application: Figure 1 is a plan view of a blank bearing divisional markings or creasings whereby a box including my improvement may be formed. Fig. 2 is a perspective view of the box end, preparatory to closing same. Fig. 3 is a similar view showing the lid closed down, with webs upstanding, and Fig. 4 is a view of the box closed.

The blank includes the rectangular divisions a b c d , whose junctures are weakened in the manner well known in this art; permitting said divisions to fold in the formation of the box. A flange e , extending from division d , and folded at right angles thereto, is cemented to division a .

The closure of one end of the box will be described; any suitable closure may be used at the other end.

Thus the division c has at its end a rectangular extension c' , which serves as a lid for the box. The extension c' has a flange c^2 along its forward edge, and said flange, being of greater length than extension c' , is provided with lugs c^3 c^4 .

Extending from the end of division a is a rectangular flap a' , intended to lie over and be cemented upon the lid c' . Between the ends of divisions b and d and the corresponding ends of extension c' are, respectively, the webs f f . These webs are triangular, and are each divided into two triangles f' and f^2 by a central line. By this means they may flex outwardly in the closing movement of lid c' .

The method of closing the box is as follows: The box end being open, and flap a' lying horizontally, as in Fig. 2, the surface of said flap is gummed. Then the lid c' is pressed downwardly to the closed position, its flange c^2 contacting with the adhesive on

flap a' , and the webs f f assuming an upright position (see Fig. 3). The webs are next laid flat upon the top of the lid, and the flap a' folded over upon them and the lid and secured thereto. In this last act, the adhesive being moist, the flange c^2 will slip in its partly formed union with the flap a' during the turning movement of the latter, so that the connection of said flap will not be ruptured, but form a clean, sharp bend. 65 The adhesive union between flange c^2 and flap a' prevents sifting of the box contents therebetween. When the flap a' has been closed down upon and cemented to the top of the box, the ears c^3 c^4 , which project laterally therefrom, are turned over upon the top surface of said flap, and cemented thereto. The function served by said ears is that of reinforcing the corners where located and of making a more complete closure at 75 said corners to prevent sifting. This latter precaution is deemed important because, in practice, when sticking the flange c^2 to flap a' it is difficult to seal the extreme end of said members as perfectly as the major interior length thereof; whereas the ears aforesaid afford a perfect closure and seal for said ends.

In opening the box, the user inserts a knife under flap a' and flange c^2 , severing 85 these members, and removing them from the box.

A further function of the lugs c^3 c^4 is that when closing the flap a' , said lugs, then extending across the box corners, and having a bearing thereon, prevent the lid c' from being pressed into the box.

I claim:

1. In a paper box, an end closure, consisting of two end panels forming respectively continuations of two opposite sides of the box, and flaps connecting the edges of the two intermediate sides of the box with the side edges of one of said end panels and foldable inwardly on top of the end 100 panel to which they are connected to form therewith a folding spout, said flaps being free to swing outwardly beyond the plane of the sides to which they are connected and being disconnected from the edges of the 105 other end panel which serves as a sealing flap for the folded spout, the end panel forming a part of the spout being provided with an anti-sifting extension overlapping the lower margin of the opposite end panel 110.

and having lateral projections limiting the inward swing of the said panel; substantially as described.

2. In a paper box, an end closure, consisting of two end panels forming respectively continuations of two opposite sides of the box, and flaps connecting the edges of the two intermediate sides of the box with the side edges of one of said end panels and foldable inwardly on top of the said panel to which they are connected to form therewith a folding spout, said flaps being free to swing outwardly beyond the plane of the sides to which they are connected and being disconnected from the edges of the other end panel which serves as a sealing flap for

the folded spout, the end panel forming a part of the spout being provided with an anti-sifting extension overlapping the lower margin of the opposite end panel and having lateral projections limiting the inward swing of the end panel, said lateral projections being of sufficient length to form flaps pasted to the outer surface of the box; substantially as described.
